UNITED STATES PATENT OFFICE.

ROBERT POTTER BREESE, OF NEW YORK, N. Y.

TOY TANK-CAR.

1,373,649.

Specification of Letters Patent.

Patented Apr. 5, 1921.

Application filed February 14, 1918. Serial No. 217,085.

To all whom it may concern:

Be it known that I, ROBERT P. BREESE, a citizen of the United States, and resident of the city of New York, in the county of New York and State of New York, have invented certain new and useful Improvements in Toy Tank-Cars, of which the following is a specification.

This invention relates to toys and is particularly directed to a toy tank car which simulates the tanks used in modern warfare or the tractors used on rocky or uneven land.

My main object is to provide a toy tank car of the character referred to above which shall be highly amusing to children, easily operated and manipulated by them, neat in appearance, compact in construction, and inexpensive to manufacture.

Further objects and advantages of this invention will appear from the detailed description and the features of novelty will be particularly pointed out in the claims.

In the drawing accompanying this specification and forming a material part thereof;

Figure 1 is an elevational view of one embodiment of this invention partly broken away to show the driving mechanism, and Fig. 2 is a similar plan view.

Referring in detail to the drawing the toy tank car is seen to be made up of a frame comprising two preferably substantially oblong side pieces 10 of the general shape and contour of tank cars or tractors and the cross pieces 11 and a top piece 12. These frame pieces may be made of wood or metal or of any other suitable material preferably colored to simulate the appearance of a tank car, and are held together in some suitable manner such as by joints or by screws 13. To further give the toy the appearance of a war tank car or a fort, metal strips 14 may be attached and these

strips have little knobs 15 punched out in them to give the appearance of rivets. These strips, too, may of course be colored to match the color of the main frame. I further provide the side pieces with properly shaped extensions 16 held thereto as by the screws 17 and projecting from these extensions are the hollow members 18 having the appearance of a cannon.

Each of the side pieces 10 is provided with a continuous chain 19 passing there-

over and held taut and guided by the idle spur wheels 20 mounted on the shafts 20' projecting from slots 21 cut in the ends of the side pieces. These chains 19 may be driven simultaneously by some suitable driving mechanism such as clock work or by a toy electric motor 22 of which the terminals 23 are supplied from a dry battery 24 by suitable connection to the battery terminals 25. One form of suitable gear and shaft arrangement is shown in the drawing and is seen to consist of a motor driven shaft 26 having on one end of this shaft a small spur gear 27 which meshes with the large gear 28 on one end of the shaft 29. This shaft 29 carries on the other end a spur gear 30 in mesh with the large gear 31 on one end of the shaft 32. The shaft 32 carries on the other end a small spur gear 33 which meshes with the large gear 34 mounted on one end of the shaft 35. On the other end of this shaft is mounted a small spur gear 36 in mesh with a large gear 37 on the shaft 38 disposed above the motor driven shaft 26. This shaft 38 also carries the small spur gear 39 which meshes with the large gear 40 mounted on the main drive shaft 41. The chain drive consists of two spur gears 42, 43 mounted on each end of the main shaft 41. These gears 42 and 43 project through suitable slots 44 in the side of the frame members 10. It will be clear from the gear as described that the motor, clock mechanism, or the like driving means may thus be made to operate the main shaft which transmits motion simultaneously to both chains.

It will be of course understood that a suitable switch 45 may be provided for closing and opening the motor circuit. A suitable resilient connector 46 may further be provided to make contact with the battery terminals when the battery is placed in position as shown in Fig. 1.

47 indicates a plate having a slot 48 at one end and a screw 49 extending through said slot into the casing, to hold the plate 47 in fixed position. A hole 50 is made in the opposite end of the plate 47 and serves as a bearing for the axle of the sprocket 105 wheel. There is a similar construction in the opposite side of the body, and by means of this construction the adjustment of the chains is effected, and thereby they are guided and kept taut.

Having thus described my invention, I claim as new and desire to secure by Letters Patent:

1. A toy tank car comprising two substantially oblong shaped vertical side pieces, tractor chains mounted on the periphery of said side pieces, means comprising an electric motor within said frame for driving said chains, and means for guiding and 10 keeping said chains taut.

2. A toy tank car comprising two substantially oblong shaped vertical side pieces, tractor chains mounted on the periphery of said side pieces, means comprising an electric motor within said frame for driving said chains, and adjustable means for guiding and keeping said chains taut. 15

3. A toy tank car comprising a frame having two substantially oblong shaped vertical side pieces, tractor chains mounted on the periphery of said side pieces, means comprising an electric motor within said frame for driving said chains, means for guiding and keeping said chains taut, and 20 means for adjusting said last mentioned means.

4. A toy tank car comprising a frame

having two substantially oblong vertical shaped side pieces, tractor chains mounted on the periphery of said side pieces, and means for driving said chains, said means comprising an electric motor, a motor shaft driven thereby, a main driving shaft carrying a driving gear on each end thereof, and means for transmitting motion from 35 said motor driven shaft to said main shaft.

5. A toy tank car comprising two substantially oblong shaped vertical side pieces, tractor chains mounted on the periphery of 40 said side pieces, said side pieces having slots formed therein adjacent the ends thereof, means within said frame for driving said chains, and means guiding said chains, said means comprising idle spur wheels projecting through said slots to be in engagement 45 with said chains.

Signed at New York, in the county of New York and State of New York this fourth day of February A. D. 1918.

ROBERT POTTER BREESE.
